JUMPING SHOES

George Pierce, Chicago, Ill., assignor to Rapaport Brothers, Inc., a corporation of Illinois
Filed Sept. 1, 1966, Ser. No. 576,742
3 Claims. (Cl. 36—7.8)

ABSTRACT OF THE DISCLOSURE

A jumping shoe having a base member and a foot support member with coil springs therebetween at the toe and heel, and stabilizing means which permits relative highwise movement between the base member and the support member but prevents sidewise movement of the foot support member relative to the base member. The stabilizing means consists of two angular members, of the same width as the base and support members, hinged to each other at one end and to the base and support members, respectively, at the other ends.

This invention relates to improvements in jumping shoes.

Jumping shoes have been on the market for a considerable period of time and they generally comprise a base member and a foot support member spaced from each other and connected by a pair of coil springs. It has been found that many children have a tendency to twist their ankles and otherwise injure themselves when using such jumping shoes, due to the fact that such devices do not have means which would prevent a side sway or buckling of the ankles. Additionally, such jumping shoes lack the ability to provide an even and smooth jump.

The foregoing disadvantages are eliminated with the present invention in which a stabilizing member is provided between the base member and the foot support member so that while there is relative movement between the foot support member and the base member to permit necessary springing action, the foot support member is controlled so that there is no sidewise pivoting or swaying from side to side. This does not impede the jumping qualities of the shoes. With this invention there is eliminated the incidence of accidents and injuries which normally attended the use of jumping shoes.

Other objects will become apparent as this description progresses.

In the drawings:

FIG. 1 is a side view of the jumping shoe forming this invention.

FIG. 2 is a view taken on line 2—2 of FIG. 1.

FIG. 3 is a view showing the stabilizing member, and

FIG. 4 is a fragmentary side view showing particularly the stabilizing member.

The jumping shoe forming this invention is indicated generally by the numeral 10 and same comprises generally a base member 12, a foot support member 14, a pair of coil springs 16 positioned between the base and foot support members and secured thereto, and a stabilizing member designated generally by the numeral 18. The stabilizing member 18 is the principal feature of this invention.

The base member 12 and the foot support member 14 have generally the same planar shape, as best seen in FIG. 2, and are formed preferably of metal. The base member 12 has a continuous upwardly extending flange 20. The base member is also provided with a plurality of spaced struck-out ears 22 at the front and at the rear to which the coil springs 16 are anchored. The opposite sides 24 of the base member are generally straight

2

but incline inwardly toward the heel portion 26 which is rounded. The front portion 27 of the base converges to a central point. Spaced longitudinally extending ribs, not shown, are formed in the base for rigidity. A plurality of spaced rubber members 28 are secured to the base member by suitable fastening elements. These members form feet on which the base rests on any surface.

The pair of spaced spiral coil springs 16 are secured to the base member by the ears 22 and by additional brackets 30 which are secured to the base member by suitable fastening rivets 32 or the like. The upper plate which is the foot support member 14 has a downwardly extending continuous flange 34 with the rear generally rounded and the front tapered or spear-shaped. The flange 34 is widened for a portion of the length to accommodate an elongated slot 36 along each of the adjacent sides to receive a strap 38 which is used to secure the front of the shoe or foot.

The upper plate or shoe support member is also provided with a plurality of punched-out spaced ears, similar to ears 22, which are intended to engage the upper convolution of the spiral springs 16. Brackets, similar to brackets 30 on the base member, are also fastened to the upper plate 14 for the purpose of completing the anchoring of the upper ends of the springs 16 to the upper plate or foot support member 14.

The foot support member 14 is provided with a plurality of spaced longitudinally extending ribs formed from the material for rigidity. The spaced rear ribs 40 serve as guides for the adjustable heel member, to be described. The upper plate 14 is provided with a centrally positioned longitudinally extending slot 42 adjacent the heel portion of the plate 14.

A metal heel support, designated generally by the numeral 44 is supported on the upper plate 14 and same is capable of longitudinal adjustment. The heel support member 44 comprises a base portion 46 and an upwardly extending arcuate-shaped rear wall 48, the opposite ends of which are slotted as at 50 to receive the ankle strap 52 which is intended to fit around the ankle of the wearer. The base portion 46 of the heel support member is provided with longitudinally extending recesses 54 which are intended to align with the rear ribs 40 on the upper plate 14. The base portion of the heel support has an opening through which extends a threaded bolt 56. The threaded bolt 56 also extends through the slot 42. A wing nut 57 is secured to said threaded bolt to lock the heel support in its adjusted position. The adjustable heel support permits shoes of different sizes to be supported on said support plate or member 14.

The stabilizing unit generally indicated by the numeral 18 comprises a pair of members generally indicated at 60 and 62 which are hinged to each other and to the base and foot support members respectively. They are made preferably of metal. The upper member 60 of the stabilizing unit has welded to it as at 61 adjacent its upper edge a hinge strip 63 which has a plurality of spaced ears 64 extending beyond the edge of the upper member 60. A hinge strip 66 is secured by suitable rivets 68 to the underside of the upper plate 14 and said hinge strip 66 has forwardly extending ears 70 spaced complementary to the ears 64 on hinge strip 63. A pin 72 extends between and connects the ears 64 and 70 to provide a hinging connection between the member 60 and the foot support member 14.

The upper member 60 has its lower end bent at an angle as at 74 and welded to said angular portion as at 75 is a hinge strip 76 having spaced hinge ears 77.

The lower member 62 of the stabilizing unit 18 is shaped similarly to the upper member 60 and hence will not be described in detail. A hinge strip 80 is secured by rivets 81 to the inside of the base member 12 and

said strip has a plurality of spaced forwardly extending ears 82. Secured by welding 83, or the like, to the lower portion of member 62 is a hinge strip 84 which has a plurality of forwardly extending ears 85 spaced alternately to the ears 82. A pin 86 extends through the ears 82 and 85 to hingedly connect the lower member 62 to the base member 12. Secured to the upper angular portion of the lower member 62, as by welding, is a hinge strip 88 which has forwardly extending spaced ears 89 to interfit with the ears 77 on the upper member 60. A pin 90 extends between the spaced ears 77 and 89 to hingedly connect the two members 60 and 62. The two members form a generally U-shaped configuration positioned sidewise.

The two hinging members 60 and 62 of the stabilizing unit 18 each have a width substantially equal to the width of the base member 12 of the foot support member 14 to which they are each respectively connected. In other words, the stabilizing unit 18 extends transversely substantially the entire width between members 12 and 14. The stabilizer will not interfere with the springiness or movement of the foot support member 14 relative to the base member 12 as the hinging connections of the stabilizer unit permit the relative movement. The jumping action is not affected. However, the side sway movement of the upper member 14 relative to the base 12 which is prevalent in the prior art devices is eliminated and all lateral sway or vertical disalignment of the upper foot support member 14 relative to the base member 12 is eliminated. The upper foot support member 14 may pivot forwardly and rearwardly but always remains in vertical alignment with the base member and cannot shift laterally with respect to the base. Thus, there is no possibility of twisting the ankle as there is no possibility of any side sway or sidewise movement. The child is provided with a firm support and is able to jump in a more even manner with safety and without injury to himself.

It will be understood that various changes and modifications may be made from the foregoing without departing from the spirit and scope of the appended claims.

What is claimed is:

1. A jumping shoe including a base member, a foot support member and spring means between said base member and foot support member, stabilizing means extending between said base and foot support members, said stabilizing means permitting relative movement between said foot support member and base member but preventing sideway movement of said foot support member relative to said base member, said stabilizing means including an upper and lower member hinged together and each also respectively hinged to the foot support member and to the base member, said upper and lower members of said stabilizing means extending transversely between the base member and the foot support member and in which each of said upper and lower members has a width substantially that of the member to which it is respectively connected.

2. A jumping shoe defined in claim 1 in which the upper and lower members are each substantially of the same shape and configuration and each has an angular portion.

3. A jumping shoe defined in claim 1 in which the foot support member has an adjustable heel support member.
